UNITED STATES PATENT OFFICE.

IRA L. MENDELL, OF ELKHART, KANSAS.

HARNESS-RING.

1,333,555.

Specification of Letters Patent.

Patented Mar. 9, 1920.

Application filed June 24, 1919. Serial No. 306,279.

To all whom it may concern:

Be it known that I, IRA L. MENDELL, citizen of the United States, residing at Elkhart, in the State of Kansas, have invented 5 new and useful Improvements in Harness Rings, of which the following is a specification.

This invention relates to a harness ring, and one object is to provide a ring through 10 which the lines controlling the bit are designed to pass, with means for preventing the lines from becoming twisted.

A further object is to provide a ring comprising a mounting element and a ring 15 member proper divided into a plurality of sections, the sections being connected by a hinge, and a dividing element being employed, preventing twisting of the line, this dividing element constituting a bar extending 20 across the ring and projecting from one surface thereof, the projecting portion being engaged by a coöperating fastening element carried by one of the hinged sections of the ring.

With the foregoing and other objects in view, the invention consists in the novel construction, combination, and arrangement 25 of elements hereinafter described and claimed.

30 In the drawings—

Figure 1 is a view of the device in elevation,

Fig. 2 is a view in vertical section,

Fig. 3 is a detail of the hinge connection,

35 Fig. 4 is a top plan view.

In carrying out my invention, I provide a ring member comprising a plurality of segmental sections, the section 10 being fixedly mounted by means of a standard, or 40 threaded pin 12, and this section 10 constituting the major portion of the ring.

The minor portion of the ring comprises an element 14 hingedly connected with element 10, as shown at 16. In order to form 45 this hinged connection, a tongue 17 is

formed on ring member 10 and element 14 is provided with a slotted portion coöperating with the aforesaid tongue. The parts are pivotally connected by means of a pin 18 passing transversely therethrough. 50

A bar 19 extends transversely of the major portion 10 and is mounted in aperture 20 in the lower portion of element 10; the opposite end passing through an aperture 21. The bar projects from the outer surface of the ring and provides an engaging element. The minor portion 14 is provided with a resilient coöperating fastening member 22 secured by a rivet 23 and having an aperture 24 adapted to engage the projecting end of bar 19, and thereby secure the hinged portion of the ring in operative or closed position. 60

As before intimated, the object of this construction is to keep the lines from becoming twisted, also to keep the buckle in the lines from becoming drawn through the ring. Under usual circumstances it frequently happens that the buckle is drawn through the ring and can not be readily released without catching, the results sometimes proving serious on account of the inability of the driver to control the lines, and therefore his inability to control the animal being driven. 70

75 What is claimed is—

In a device of the class described, a ring comprising a major and a minor portion, the portions being hingedly connected, mounting means for the major portion of the ring, a bar extending transversely of said major portion and projecting beyond the surface of the ring, a resilient fastening device carried by the minor portion of the ring and provided with an aperture, said aperture being adapted to engage the projecting end of the bar. 80

85 In testimony whereof I affix my signature.

IRA L. MENDELL.
